CLAIM

The ornamental design for a fishing reel portion, as shown and described.

DESCRIPTION

FIG. 1 is a first perspective view of a fishing reel with a fishing reel portion in accordance with my new design;

FIG. 2 is a second perspective view of the fishing reel with the fishing reel portion illustrated in FIG. 1;

FIG. 3 is a first side elevational view of the fishing reel with the fishing reel portion illustrated in FIG. 1;

FIG. 4 is a second side elevational view of the fishing reel illustrated in FIG. 1;

FIG. 5 is a top plan view of the fishing reel with the fishing reel portion illustrated in FIG. 1;

FIG. 6 is a bottom plan view of the fishing reel with the fishing reel portion illustrated in FIG. 1;

FIG. 7 is a first end elevational view of the fishing reel with the fishing reel portion illustrated in FIG. 1;

FIG. 8 is a second end elevational view of the fishing reel with the fishing reel portion illustrated in FIG. 1; and,

FIG. 9 is a first enlarged, partial perspective view of the fishing reel with the fishing reel portion illustrated in FIG. 1 that shows a plain weave, carbon fiber cloth pattern that produces a checkerboard-like appearance, which appears over the entire surface of the fishing reel portion illustrated in FIGS. 1 to 8.

The broken line showing of the fishing reel is for purpose of illustrating environmental structure and forms no part of the claimed design.
